UNITED STATES PATENT OFFICE.

HENRY B. ROBISCHUNG, OF KALAMAZOO, MICHIGAN, ASSIGNOR TO THE CHICAGO RAILWAY EQUIPMENT COMPANY, OF CHICAGO, ILLINOIS.

BRAKE-BEAM.

SPECIFICATION forming part of Letters Patent No. 508,051, dated November 7, 1893.

Application filed June 8, 1893. Serial No. 477,006. (No model.)

To all whom it may concern:

Be it known that I, HENRY B. ROBISCHUNG, a citizen of the United States, residing at Kalamazoo, in the county of Kalamazoo and State of Michigan, have invented certain new and useful Improvements in Brake-Beams; and I hereby declare the following to be a full, clear, and exact description of the same, reference being had to the accompanying drawings, 55 wherein—

Figure 1 is a plan view, partly in section, of a trussed brake beam embodying my invention. Fig. 2 is an enlarged horizontal sectional view of one end of the beam or compression member, a cup or sleeve thereon, the brake head, end cap, and nut of the tension member, the end of the tension member being shown in elevation. Fig. 3 is a sectional view of the parts last recited taken at right angles to Fig. 2 on the line $x-x$ thereof. Fig. 4 is a side elevation of the cup or sleeve. Fig. 5 is an end elevation of the cup or sleeve. Fig. 6 is a longitudinal central section of the cup or sleeve on the line $y-y$, Fig. 5. Fig. 7 is a side elevation of the brake-head. Fig. 8 is a view of the exterior or convex surface of the end cap. Fig. 9 is a side elevation of the end cap, and Fig. 10 is a view of a cotter or split pin for securing the cap to the end of the beam or sleeve. Fig. 11 is a sectional view of the construction as applied directly to the end of a beam.

Like symbols refer to like parts wherever they occur.

My present invention relates to certain improvements in the means for securing the end cap to the beam, whereby the cap is forced against the head and so binds the same as to clamp it to the beam after the head has been 75 adjusted to the line of draft or applied power, and with relation to the wheel; and while it may be generally mentioned as an improvement on the devices therefor, covered by Letters Patent No. 494,709, dated April 4, 1893, it is 80 not to be understood as limited thereby in its application, as the corrugations of head and beam flange shown in said recited Letters Patent, if desired, may be omitted from the combinations of the present invention, and 85 for purposes of illustration, have in fact been so omitted.

The invention, broadly stated, embraces the combination with the perforated beam end of a perforated cap, the axial centers of the perforations in cap and beam being different, and a through pin or its equivalent, whereby a cam or wedge mechanism is obtained to force the cap down on its seat and securely clamp the brake-head to the beam.

I will now proceed to describe my invention 90 more fully, so that others skilled in the art to which it appertains, may apply the same.

In the drawings A indicates the compression member or beam proper, B the strut or post, C a sleeve or cup on the end of the beam, 95 D the tension rod threaded at its ends and provided with tension nuts d , E suitable brake-heads, F, F, end caps which house the end of the tension rod, and tension nuts, and G, G, split keys or cotters which secure the 100 end caps to the beam and cause the end caps to clamp and confine the brake heads.

It is to be understood, that the brake beam is not necessarily a trussed beam, as the beam may be of any desired character; it is also to 105 be understood that the detachable cups or sleeves C C are not essential features, as the equivalent thereof—the bearing flange or seat for the inner face of the brake-head—may be formed or permanently attached to the beam 110 A; however for purposes of illustration I have chosen a trussed cambered brake beam, of a form now well known, and detachable end cups or sleeves. Said sleeves C, C, (or the beam) are provided with bearing flanges e for the 115 inner faces of the brake-heads, which flanges are shown plain, but may be either plain or corrugated, and if the head is to be adjustable the sleeves should be in the nature of journals upon which the brake-head, after it 120 is on, may be rotated to present the brake shoe properly to the wheel, said position to be determined by the line of applied power, the point of suspension of the brake-beam, the height of brake beam above the track, the 125 structure of the beam, and other conditions well understood by those skilled in the art. The outer end of each sleeve (or of the beam) may be perforated or provided with a pin hole c , the bore of which has at midlength a 130 swell or cam surface c' , (see Fig. 3,) adapted to force the key or pin off the axial line.

Each of the end caps F F, is also pierced as at f f, for the passage of the cotter or split pin, said holes f—f, having their axial centers coincident with each other but not coincident with the axial center of the bore c in the end of the beam—when the end cap is in position, as shown in Figs. 1, 2 and 3—so that when the cotter G is inserted the cotter and swell c' form a wedge or cam mechanism which forces the end cap down on the outer face of the brake-head E E.

The construction being substantially such as hereinbefore specified, the parts are assembled on the ends of the beam, as indicated in Figs. 1 and 2, the split pin or cotter G is inserted and driven home as indicated in Fig. 3—which draws or forces the end caps F F, toward the transverse center of the beam and securely clamps the brake-heads E E, between the flanges e, e, and the rims of the end caps F F, retaining them in whatever position they may be when the cotters are inserted.

Having thus described my invention, what I claim, and desire to secure by Letters Patent, is—

1. The combination with a brake beam hav-

ing a seat or bearing flange for one side of the brake-head, of a brake-head, an end cap, and cam or wedge mechanism for forcing the end cap against the other side of the brake-head, substantially as and for the purpose specified.

2. The combination with a brake beam having a seat or flange for one side of the brake head and a cotter hole having a swell within the bore thereof, of a brake-head, an end cap having cotter holes, and a cotter or pin, substantially as and for the purposes specified.

3. The combination with a brake beam having a seat for one side of a brake head and a cotter hole, of a brake head, an end cap having cotter holes on a different center from the axis of the cotter hole in the end of the beam, and a cotter or pin for securing the cap to the end of the beam and confining the brake-head, substantially as specified.

In testimony whereof I affix my signature, in presence of two witnesses, this 5th day of June, 1893.

HENRY B. ROBISCHUNG.
